UNITED STATES PATENT OFFICE.

SAMUEL A. SPITZ, OF DAVID CITY, NEBRASKA, ASSIGNOR OF ONE-HALF
TO PETER B. GAINER, OF DAVID CITY, NEBRASKA.

CULTIVATOR.

No. 814,567.

Specification of Letters Patent.

Patented March 6, 1906.

Application filed August 25, 1905. Serial No. 275,812.

To all whom it may concern.

Be it known that I, SAMUEL A. SPITZ, a citizen of the United States, residing at David City, in the county of Butler and State of Nebraska, have invented a new and useful Cultivator, of which the following is a specification.

This invention relates to riding-cultivators; and it has for its object to promote simplicity, durability, and general efficiency in the construction and operation of this class of devices, to improve the draft attachment so that the draft may be applied evenly and without excessive strain upon any of the parts of the device and at a low-down point where it will be most efficiently applied, and to provide for the adjustment of the axis upon which the frame is supported, so that the said frame may be evenly balanced according to the weight of the driver.

With these and other ends in view, which will readily appear as the nature of the invention is better understood, the same consists in the improved construction and novel arrangement and combination of parts, which will be hereinafter fully described and particularly pointed out in the claims.

In the accompanying drawings has been illustrated a simple and preferred form of the invention, it being, however, understood that no limitation is necessarily made to the precise structural details therein exhibited, but that the right is reserved to any changes, alterations, and modifications to which recourse may be had within the scope of the invention and without departing from the spirit or sacrificing the efficiency of the same.

In said drawings, Figure 1 is a side view of a riding-cultivator constructed in accordance with the principles of the invention, said view being partly in section. Fig. 2 is a rear elevation of the same. Fig. 3 is a perspective detail view of the draft attachment. Fig. 4 is a perspective detail view of one of the sockets for the attachment of the cultivator-beams. Fig. 5 is a perspective detail view of one of the connecting and adjusting links. Fig. 6 is a detail rear elevation of a cultivator-blade of a construction slightly different from that shown in the remaining figures.

Corresponding parts in the several figures are indicated throughout by similar characters of reference.

The frame of the machine includes a cross-

bar 1, preferably of circular cross-section and which is connected securely, as by means of a clip 2, to the under side of the tongue 3. Said cross-bar supports near the ends thereof a pair of links 4 4, (shown in detail in Fig. 5 of the drawings,) each of said links consisting of a suitably-shaped block or casting having two parallel bores 5 and 6, the former of which engages the cross-bar 1.

7 7 are a pair of side frame members, each consisting of a link rod or bar bent at each end, the forward end of each of said bars being in pivotal engagement with the bore 6 of one of the links 4. The bent portions 8 at the rear ends of the bars 7 constitute spindles upon which the carrying-wheels 9 are supported for rotation.

Firmly secured upon the sides of the tongue are the forward extremities of a pair of frame-bars, which latter include parallel portions 10 10 and laterally-extending converging portions 10' 10', which latter terminate in the bent portions or bracket members 12', engaging opposite sides of the tongue and secured to the latter, as by transverse bolts 14'. Upon the under sides of the parallel portions 10 10 of these frame-bars and upon the upper sides of the frame-bars 7, near the hubs of the wheels, are secured perforated lugs 11, which are connected and spaced apart by means of links 12.

Pivoted upon one of the frame-bars 10 is one end of the seat-support, which in the present instance has been illustrated as comprising two spaced parallel bars 13, slightly curved downwardly and supporting the seat 14. The free ends of the bars constituting the seat-support terminate in hooks 15, which are supported upon the opposite frame-bar 10. Set-collars 16 serve to retain the seat-support adjustably upon the frame-bar 10, with which it is pivotally connected. By the construction described the free end of the seat-support may be raised when desired to enable the driver to step in front of the seat previous to mounting, thus facilitating access to the seat.

Each of the links 4 is provided in one side thereof with a notch or recess 17, in which is seated a lever 18, having a stop 19, adapted to engage a perforated segment 20, one of which is mounted upon each of the frame-bars 10. It will be seen by manipulating said levers the links may be partially rotated upon

the frame-bar 1, so as to move the frame members 7 in a forward or in a rearward direction, as may be desired, the link connection 12 between the frame members 7 and 10 enabling such adjustment to take place for the purpose of adjusting the axis of the carrying-wheels forwardly or rearwardly, as may be desired, according to the weight of the driver, and thus causing the entire frame 10 to be evenly balanced. It is obvious that a preliminary longitudinal adjustment of the seat may first be made; but experience has proven the desirability of a perfectly accurate adjustment to cause the implement to be 15 evenly balanced, and this important object may be satisfactorily attained by the simple construction and arrangement of parts just described.

Upon the frame-bar 1 are pivotally mounted 20 a plurality of levers 21, said levers being mounted adjustably between set-collars 22. The upper ends of these levers are connected in pairs by link-bars 23, and said link-bars, which are disposed in front of the upper ends 25 of the levers 21, are connected by central pivotal pins or bolts 24 with a pair of eveners-bars 25, disposed adjacent to the upper and under sides of the link-bars 23. The eveners-bars 25 are centrally pivoted upon a standard 30 26, extending upwardly from the tongue 3 near the rear end of the latter, said standard being reinforced by an obliquely-disposed brace 27.

The draft is attached to the lower ends of 35 the levers 21, which are provided with hooks 28, to which the tugs or traces of the draft-animals are directly attached, the use of ordinary swing and double trees being thus entirely avoided. This draft attachment is 40 considered an important feature of the invention, for the reason that the draft may be applied at a point not far above the ground, where it is most effective and where it will most readily yield to steering, while the absence of swingtrees avoids hampering the 45 heels of the animals, which are thereby frequently annoyed and irritated when draft attachments of ordinary construction are used.

Upon the frame-bar 1 are mounted a pair 50 of sleeves 29 of the construction shown in detail in Fig. 4 of the drawings, by reference to which it will be seen that said sleeves are provided upon their front sides with socket members 30, having bores extending vertically therethrough for the passage of the front ends of the cultivator-beams 31, which are retained in the bores of said socket members by means of set-collars 32, whereby vertical 55 adjustment of said beams may be conveniently effected. In like manner the sleeves 29 may be adjusted laterally upon the frame-bar 1 by means of set-collars 33, between 60 which they are secured. The beams are extended rearwardly and are curved down-

wardly to form standards 34, auxiliary standards 35 being secured to said beams in the usual manner. The beams are equipped with handles 36, whereby they may be conveniently manipulated by the operator, and 70 with foot-rests 37, enabling the operator to press the standards downwardly with his feet. Upon the inner sides of the side members 7 are provided hooks 38, upon which the standards may be supported when lifted from 75 the ground for transportation.

The preferred form of blades has been illustrated in Figs. 1 and 2 of the drawings, by reference to which it will be seen that said blades are made right and left hand, so that 80 by exchanging from one side to the other they may throw dirt toward or from the row of plants that is being operated upon, according to the nature of the work. Said blades, which are designated 39, are provided with 85 oblique upper edges, (indicated at 40,) and said blades are properly twisted to constitute moldboards for the purposes indicated. In lieu of the blades illustrated in Figs. 1 and 2 of the drawings the special blade 41 (shown 90 in Fig. 6) may be used, said blade being adapted for straight work and therefore provided with a straight upper edge, while the contour of the blade is marked by the absence of any twist therein beyond the longitudinal curvature.

From the foregoing description, taken in connection with the drawings hereto annexed, the operation and advantages of this invention will be readily understood by those 100 skilled in the art to which it appertains.

It will be observed that the frame is extremely light and therefore easily propelled, that the draft attachment is such as to enable the power exerted by the animals to be 105 most profitably employed, and that the provisions made for balancing the frame with regard to the weight of the driver or operator are conducive to lightness of draft and to effectiveness in the operation of the device as 110 a whole.

Having thus described the invention, what is claimed is—

1. In a riding-cultivator, a tongue, a pair of parallel frame-bars having converging 115 front ends secured upon the sides of the tongue, a cross-bar secured upon the under side of the tongue, links pivoted upon said cross-bar and having operating-levers, wheel-carrying bars connected pivotally with the 120 links and terminating at their free ends in spindles upon which the carrying-wheels are supported for rotation, and auxiliary links connecting the wheel-carrying bars with the parallel frame-bars.

2. In a riding-cultivator, a tongue, a pair of parallel frame-bars having converging front ends secured upon the sides of the tongue, a cross-bar secured upon the under side of the tongue, links pivoted upon said 130

cross-bar and having operating-levers connected therewith, wheel-carrying bars connected pivotally with the links and terminating at their free ends in spindles upon which

5 wheels are supported for rotation, auxiliary links connecting the wheel-carrying bars with the parallel frame-bars, seat-supporting bars hingedly engaging one of the frame-bars and having hook-shaped ends loosely engag-
10 ing the other frame-bar, and collars adjust-
ably engaging one of the frame-bars adjacent

to the hinged ends of the seat-supporting members to retain the latter at various adjustments upon the frame-bar.

In testimony that I claim the foregoing as 15 my own I have hereto affixed my signature in the presence of two witnesses.

SAMUEL A. SPITZ.
